JOHANNES ROBERT CARL AUGUST, OF SOWERBY BRIDGE, ENGLAND.

MACHINE FOR WRAPPING SMALL ARTICLES.

1,187,414.

Specification of Letters Patent. Patented June 13, 1916.

Application filed June 30, 1915. Serial No. 37,281.

To all whom it may concern:

Be it known that I, JOHANNES ROBERT CARL AUGUST, a subject of the King of Great Britain, residing at The Hollins, Sowerby Bridge, in the county of Yorkshire, England, have invented certain new and useful Improvements in Machines for Wrapping Small Articles; and I do hereby declare the following to be a full, clear, and exact description of the invention, such as will enable others skilled in the art to which it appertains to make and use the same.

The present invention relates to improvements in machines for wrapping small articles as for instance toffee. Hereafter the term "toffee" will be used for brevity but it is to be understood that this term includes other small articles.

The object of the invention is to provide a machine for the above purpose which is capable of being run at a high speed the operation of which will, at the same time, not be affected by small irregularities in the shape and size of the article to be wrapped.

The invention will be described with reference to the accompanying drawings in which:—

Figure 1 is a sectional side elevation of the wrapping and twisting mechanism. Fig. 2 is a front view of Fig. 1. Fig. 3 is a plan view of Fig. 1. Fig. 4 is a diagram of an electric circuit employed in connection with the machine. Fig. 5 is a side elevation of the toffee feeding mechanism. Fig. 6 is a view of the relative positions of the toffee and wrapper as it is fed to the folding devices. Fig. 7 is a plan of a portion of a conveyer and means shown as in Fig. 5 for supplying a battery of feed hoppers with toffees therefrom.

In these drawings two elastic belts or bands 1 preferably of vulcanized rubber are employed one above the other, being mounted on pulleys or supporting rollers 2 in such a manner that the lower run of the upper belt is in close proximity to the upper run of the lower belt. The guide pulleys of the upper belt are placed somewhat forward of the guide pulleys of the lower belt. These pulleys 2 are mounted as regards the driven pulley of the upper belt on a shaft 18 and as regards the driven pulley of the lower belt on a shaft 6. The shaft 6 carries a driving pulley 5 and is continuously rotated in the operation of the machine. This shaft 6 carries a pinion 21 which meshes with an

intermediate toothed wheel 20 which in its turn engages with a toothed wheel 19 revolvably mounted on the driving shaft 18 of the upper band. Connected to this wheel 19 is an armature 16 in the form of a disk. Keyed on the shaft 18 there is a drum 17 containing an electromagnet 10. Also keyed on the shaft 18 is a commutator 23 having brushes 25 located in an electric circuit such as shown in Fig. 4. One of the rings of the commutator 23 has an insulated space 24. Mounted one on each side of the belts or bands is a gripping device consisting of a solenoid 9 with a core 11. On the upper projection of this core which passes up through a frame 13 there is mounted a jaw 12. In this frame 13 is mounted a second jaw 15 which by means of a rack on its downward extension is connected by means of a small pinion 14 to a similar rack on the upward extension of the core 11. The solenoids 9 are arranged in a circuit with the electro-magnet 10 and a switch consisting of terminals 7, 8 is located under the upper run of the lower band 1 being arranged in the electric circuit above referred to.

The action of the device so far described is as follows:—The toffee 3 with a piece of paper 4 partially around it as shown in Fig. 6 which is effected in the manner hereinafter described is placed upon the projecting portion of the lower belt or band and travels along on the same till it comes into contact with the upper belt. The lower belt continues its motion and so rolls the toffee forming the paper around it into a tube. The toffee forms a bulge in the bands and causes the lower band to press against the terminal 7 and so closes it down on to the terminal 8 closing the electric circuit shown in Fig. 4 with the result that the cores 11 in the solenoids 9 are immediately pulled down gripping the ends of the tube of paper, formed as above described and as shown in dotted lines in Fig. 3, between the jaws 12 and 15 holding the same stationary. At the same time, as the electro-magnet 10 is operated, the armature disk 16 is locked against the drum 17. As the toothed wheel 19 is continually and freely revolved on the shaft 18 the motion of the same will be transmitted through the disk 16 to the drum 17 and so to the shaft 18 causing the shaft 18 to rotate in the same direction as the shaft 6 which will cause the under run of the upper band 1 to be moved in an opposite direction

to the upper run of the lower band 1, the two bands being moved at exactly the same speed with the result that the toffee and piece of held paper will as a whole remain stationary but will be spun about its own axis with the ends of the paper held clamped between the jaws 12 and 15 so twisting up the ends of the paper tube. On however the shaft 18 making practically a complete revolution the 10 insulated portion 24 will come under one of the brushes 25 and so open the electric circuit immediately deenergizing the solenoids 9 and releasing the jaws 12 and 15 and so freeing the paper tube about the toffee. This 15 breaking of the circuit will also deenergize the electro-magnet 10 and so release the drum 17 from the disk 16 and thereby cause the shaft 18 to stop. A slight further movement of the lower band 1 will move the toffee 20 from over the terminal 7 and so open the electric circuit at a second place. The drum 17 will have a sufficient momentum to carry the insulated portion 24 just past the brush 25 so that the electric circuit will again be 25 closed except for the switch 7, 8 which will be closed when the next piece of toffee comes over the part 7. The continued travel of the lower band 1 will eject the toffee with the ends of the tube surrounding it twisted up 30 from between the bands into any suitable receptacle.

To compensate for the natural decrease in the length of the tube of paper about the toffee as it is twisted the solenoids 9 are 35 swung on suitably held screws 28 which permit of their swinging somewhat about a horizontal axis. The axis about which they swing is so located that these solenoids and jaws will normally remain in such a position 40 that the cores 11 will re-assume a vertical position on being released from the paper wrapping.

To afford a suitable feed of the toffees and papers in the position shown in Fig. 6 45 to the bands the following arrangement is adopted. A chute 34 is arranged in which the toffees 3 are placed one above the other as shown by means hereinafter described so that the lowest of the toffees lies in a horizontal passage 36. In one end of this passage there is mounted a plunger 35 which is connected by a suitable cross bar 35^a to suitable guide rods 47 located one on each side of the machine and normally held in the position 50 in which the plunger 35 is retracted by springs 58. The forward ends of the rods 47 are connected by suitable pivot connections to an arm 46 of a swinging yoke 43 of which there is one mounted on each side of the machine being pivoted about suitable 55 bearings 44. This yoke is provided with a curved arm 46^a concentric with the center about which the yoke turns. The shaft 45 upon which the toothed wheel 20 is mounted 60 carries at each end a cam 48 which contacts

with a stop 49 on the yoke 43 in the revolution of the shaft 45. The chute or passage 36 just past the chute 34 is provided with a passage 37 at right angles up into which the wrapping paper 4 passes. This paper passes 70 between suitably mounted resiliently covered rollers 38 concentric with one of which there is arranged a toothed wheel 39 which is connected up to the toothed wheel 42 on the shaft 6 by an idle wheel 40 mounted on a 75 swinging plate 41. This plate 41 is connected by a link 53 to one of two levers 51 which are arranged toward each side of the machine and are suitably pivoted at 52. These levers 51 each carry at their upper end a 80 roller which lies in the path of the projection 50 mounted underneath the plunger 35. These levers are also connected to a frame 55 on which is mounted a gripping plate 55^a normally held in its outward position by 85 springs 57. The frame 55 at the same time carries a knife 54. Located below and to the other side of the chute 37 is a stationary recessed block 56.

The action of this part of the device is 90 as follows—The shaft 6 in its rotation rotates the cam 48 which acts against a stop 49 on the yoke 43 which owing to its engagement with the rods 47 pushes forward the plunger 35 and so displaces one piece of 95 toffee from the chute 34 along the passage 36. As the toffee is brought into contact with the paper chute 37 the projections 50 come into contact with the lever 51 which swings the plate 41 somewhat so as to throw 100 the idle wheel 40 out of gear with the toothed wheel 38 and so stops the forwarding of the paper by the rollers 38. At the same time the frame 55 is forced forward till the gripping plate 55^a presses the paper 105 against the grooved plate or block 56. A further movement of the frame 55 causes the knife to move forward relative to the gripping block 55^a causing it to enter somewhat into the recess in the block 56 and sever the paper. The further movement of the plunger forces the toffee together with the cut off piece of paper on to the upper run on the lower band in the position shown 110 in Fig. 6 in which condition it is acted on by the two bands 1 in the manner above described. When the cam 48 passes the stop 49 the plunger 35 and its appurtenances are forced back owing to the springs 58 ready 115 to force the next piece of toffee.

To make it possible to feed a battery or 120 number of above described machines from one central feed the arrangement shown in Figs. 5 and 7 is adopted. In connection with each machine there is a hopper 27. 125 Over this hopper there is arranged a conveyer band 59 upon which the toffees are placed. In connection with each hopper there is arranged a deflecting plate or baffle 60 which baffles progressively project some- 130

what more over the belt 59 so as to deflect a given quantity of the pieces of toffee into each trough 27. At the bottom of each of these troughs 27 is a traveling band 22 mounted on suitable rollers 30 which band 22 is provided with ribs or projections 29 at such a distance apart as to accommodate one toffee between each two ribs. At the end of each hopper 27 there is arranged a chute 33 which is curved around the forward roller 30 and continued to point over the chute 34 of the respective machine. A constantly rotating wheel 31 with arms 32 is arranged in connection with each of the troughs 27 which continually throws back the surplus toffees, which accumulate on the band 22, to the rear of the hopper 27.

I claim:—

1. In a machine for wrapping small articles, provided with a strip of paper projecting at each side beyond the article to be wrapped, means comprising two endless belts, with means for moving same for rolling the article and the piece of paper bodily together to place the paper around the article, subsequent means for rotating the article and surrounding piece of paper about their own axis, means for holding the projecting sides of said paper during the rotation of said paper and article about their own axis and means for subsequently releasing said paper and said article.

2. In a machine for wrapping small articles, means for placing a piece of paper around the article so that the sides of the paper project somewhat beyond the article, means for gripping the paper by the projecting ends, means for rotating the article about its own axis, said means comprising two endless belts, with means for moving same and means for subsequently releasing the paper and article.

3. In a machine for wrapping small articles, two parallel bands in close proximity to the one to the other, means for inserting between said bands the article to be wrapped and a suitably sized piece of paper which projects somewhat beyond the article to each side in a direction crosswise of the said bands, means for forwarding one of said bands relative to the other, means for moving the other band at given periods in a direction opposite and at the same speed as the first band, means for gripping the paper by its projecting sides during the period that the second band is being forwarded and means for subsequently releasing said article and paper.

4. In a machine for wrapping small articles, two endless bands mounted with the lower run of one band parallel to and in close proximity to the upper run of the lower band, means for supporting the bands in these relative positions, means for inserting the article to be wrapped and a piece

of paper of such a size as to project somewhat beyond the sides of the article and beyond the sides of the bands between said bands, means for forwarding one of said bands to roll the article and piece of paper 70 bodily against the other band for a given period, means for forwarding the adjacent run of the other band in an opposite direction at and for a given period, means for holding the projecting sides of the paper 75 during this last mentioned period and means for subsequently releasing said paper and articles.

5. In a machine for wrapping small articles, an endless band, means for continuously traveling said band, a second endless band located over and in close proximity to and parallel to the first band, means for forwarding said second band periodically in such a direction that the adjacent runs 85 of said bands run in opposite directions, means for placing the article to be wrapped and a piece of paper which projects somewhat beyond the article to be wrapped and beyond the sides of the bands between said 90 bands, means for gripping the projecting ends of the piece of paper at such periods as the second band is forwarded and means for subsequently releasing the paper.

6. In a machine for wrapping small articles in pieces of paper, means for folding the paper around the article to form a tube the ends of the tube so formed projecting from the article, jaws located to close on the ends of the tube formed by the piece of paper about said articles, means for actuating said jaws, means for turning the paper and the inclosed article about their own axis when the ends of the paper are gripped by said jaws, said means comprising two endless belts, with means for moving same, and means for subsequently releasing the article and paper from said jaws.

7. In a machine for wrapping small articles two endless belts located with their 110 runs parallel one being located above and in close proximity to the other, rollers supporting said bands, means for continuously rotating the rollers of the lower band, means for placing the article to be wrapped and a 115 piece of paper the sides of which project beyond the article and beyond the sides of the bands on the lower of said bands, jaws located one set on each side of and in proximity to the adjacent runs of the two said 120 bands, means for operating said jaws to grip the projecting portions of the paper about said article, means for actuating said jaws when said paper comes opposite said jaws, means for forwarding the upper of 125 said bands to turn the article and piece of paper surrounding it about their own axis when said jaws are closed, means for subsequently releasing the article and the paper surrounding the same.

8. In a machine for wrapping small articles in paper, two endless bands, rollers supporting said bands with the lower run of one band parallel to the upper run of the other band, means for continuously actuating the lower band, a shaft supporting said rollers, a toothed wheel loosely mounted on the shaft supporting one of the rollers of the upper band, means for continuously rotating said loose toothed wheel, an electro-magnet keyed to said shaft, an armature keyed to said toothed wheel and means for energizing said electro-magnet at such periods as said upper band is to be traveled, means for inserting an article with a piece of paper with its sides projecting beyond the article and beyond the bands between said bands, a gripping device for holding the projecting sides of the paper at such times as the upper band is actuated and means for releasing said article and paper.
9. In a machine for wrapping small articles two endless bands located with the lower run of one band immediately over the upper run of the other band, rollers supporting said bands, means for rotating said rollers, clutch means intermediate the rollers of said upper band and said means for rotating said rollers, gripping jaws located at each side of said bands, controlling means for simultaneously closing said jaws and engaging said clutch means to connect the rollers of the upper band with the roller rotating means.
10. In a machine for wrapping small articles, two endless bands located with the lower run of one band immediately over the upper run of the other band, rollers supporting said bands, means for rotating said rollers, clutch means intermediate to the rollers of said upper band and said roller rotating means, gripping devices located one at each side of said bands, electro-magnetic means controlling each of said gripping devices, electro-magnetic devices controlling said clutch means, an electric circuit comprising said different electro-magnetic means, a switch in close proximity to the adjacent runs of the said belts also in said electric circuit.
11. In a machine for wrapping small articles, two endless bands located with the lower run of one band immediately over the upper run of the other band, rollers supporting said bands, means for rotating said rollers, clutch means intermediate the rollers of said upper band and said means for rotating said rollers, gripping jaws located at each side of said bands, controlling means for simultaneously closing said jaws and engaging said clutch means to connect the rollers of the upper band with the roller rotating means in combination with a channel, a chute over and in communication with said channel for receiving the articles, a chute for a strip of paper between said article chute and the lower of said bands, means for forcing a strip of paper up said paper chute, means for severing pieces from said paper, a plunger in said passage, means for operating said plunger to displace one article and the severed piece of said paper along said passage on to the lower of said bands and means for retracting said plunger.
12. In a machine for wrapping small articles, a plurality of devices each consisting of two endless bands, located with the lower run of one band immediately over the upper run of the other band, rollers supporting said bands, means for rotating said rollers, clutch means intermediate the rollers of said upper band and said means for rotating said rollers, gripping jaws located at each side of said bands, controlling means for simultaneously closing said jaws and engaging said clutch means to connect the rollers of the upper band with the roller rotating means, a chute for containing said articles, means for supplying a piece of paper to the machine for each article, a hopper and means for feeding the articles one by one from said hopper to said chute in combination with a conveyer band and a baffle projecting from each hopper over said conveyer band said baffles extending progressively farther over said band to direct articles from said conveyer to said hoppers.
13. In a machine for wrapping small articles, two endless bands located with the lower run of one band immediately over the upper run of the other band, rollers supporting said bands, means for rotating said rollers, clutch means intermediate the rollers of said upper band and said means for rotating said rollers, gripping devices located one at each side of said bands, said gripping devices each consisting of a solenoid, means for mounting said solenoid about a horizontal axis parallel with the bands, a core, an extension from said core, a jaw mounted on said extension, a casing, a second jaw slidably mounted in said casing and means between said core and said second jaw to move the said second jaw in the opposite direction to that in which the core is moved and to close the jaws one on the other, said jaws when closed having their point of contact on a level with the adjacent runs of the bands, a switch located in proximity to the adjacent runs of said belts adapted to be operated by a bulge in said bands formed by the article between the adjacent runs of said bands and an electro-magnet operating said solenoid and said switch.
14. In a machine for wrapping small articles, two endless bands located with the lower run of one band in close proximity and parallel to the upper run of the lower band, means for operating said bands to firstly re-

- ceive an article to be wrapped and a piece of paper of a size to project beyond the bands between them, secondly roll the article and paper between them, thirdly to revolve the article and paper about their own axis without traveling, and fourthly to eject the article and paper in combination with two sets of jaws one on each side of the adjacent runs of the bands and means closing said jaws on to the projecting portion of the paper during the period the said bands are operated to revolve the article and paper about their own axis.
15. In a machine for wrapping small articles in separate pieces of paper, provided with a strip of paper of a width to project at each side beyond each article to be wrapped, means for placing each article on a piece of said paper, means for rolling said article and said paper against a stationary surface, means for subsequently holding the part of the paper projecting beyond the article and simultaneously rotating the article and paper and means for subsequently releasing the article and paper.
- 20
- 25
16. In a machine for wrapping small ar-

articles in separate pieces of paper, provided with a strip of paper of a width to project at each side beyond each article to be wrapped, means for placing each article on a piece of said paper, means for rolling said article and said paper against a stationary surface, means for subsequently holding the part of the paper projecting beyond the article and simultaneously rotating the article and paper and means for subsequently releasing the article and paper in combination with a chute, a passage leading from said chute to said means for rolling the article, a second chute traversing the closed passage between said first chute and said rolling means, means for intermittently feeding a strip of paper up into said second chute, means for periodically severing pieces from said strip of paper and means for forward- 45

ing an article from said first chute together with a severed piece of paper on to said means for rolling the article and piece of paper.

In testimony whereof, I affix my signa- 50

ture.

JOHANNES ROBERT CARL AUGUST.
